United States Patent Office

Des. 202,589
Patented Oct. 19, 1965

202,589

SEWING MACHINE

Henry Dreyfuss, South Pasadena, Calif., assignor to The
Singer Company, New York, N.Y., a corporation of
New Jersey

Filed Sept. 18, 1964, Ser. No. 81,777

Term of patent 14 years

(Cl. D70—1)

Fig.1

Fig.2

Fig.3

Fig.4

Fig.5

Fig.6

Fig.7

FIG. 1 is a front perspective view of a sewing machine, showing my new design,

FIG. 2 is a rear perspective view thereof,

FIG. 3 is a front elevational view thereof,

FIG. 4 is a rear elevational view thereof,

FIG. 5 is a head-end elevational view thereof,

FIG. 6 is a standard-end elevational view thereof, and

FIG. 7 is a top plan view thereof.

I claim:

The ornamental design for a sewing machine, substantially as shown.
